TWO-TERMINAL LOW-PASS COUPLING SYSTEM

Harold A. Wheeler, Great Neck, N. Y., assignor to Hazeltine Corporation, a corporation of Delaware

Application April 22, 1938, Serial No. 203,597

10 Claims. (Cl. 178—44)

This invention relates generally to low-pass coupling systems and particularly to low-pass coupling systems including a pair of terminals in parallel with which there is substantial capacitance and across which it is desired to build up a high impedance or admittance which is substantially constant over a wide range of frequencies.

In many low-pass coupling systems it is desirable to build up a substantially uniform impedance having the highest possible mean value over a wide range of frequencies between terminals having susceptance in parallel therewith; that is, it is desirable to maintain approximately the maximum mean value of impedance between the terminals over a wide range of frequencies. For example, in the design of vacuum-tube amplifiers to pass a wide band of frequencies, it is desirable to build up across capacitance, comprising the inherent capacitances of the tube circuits to be coupled, the maximum impedance that can be maintained substantially uniform over the operating frequency band of the amplifier, such impedance being limited by the inherent capacitances of the tube circuits to be coupled. Prior art coupling arrangements utilized for this purpose have fallen far short of the desired results.

It is an object of the present invention, therefore, to provide a low-pass coupling system comprising a pair of terminals across which there is shunt susceptance and across which a maximum and substantially constant value of impedance is maintained over a wide range of frequencies.

It is another object of the invention to provide a low-pass coupling system having maximum impedance over a wide frequency range for use between two successive tubes of a vacuum-tube amplifier.

In accordance with one embodiment of the invention, a two-terminal low-pass signal-translating system for operation over a wide range of frequencies comprises a pair of terminals common to the input and the output circuits of the system across which there is effectively capacitance tending to limit the response of the system over its range. A dead-end filter having a predetermined image impedance over the range is coupled to the terminals, the filter comprising only a part of the capacitance across the terminals as a terminal mid-shunt element. An impedance termination is provided coupled to the dead-end of the filter proportioned substantially to match the image impedance of the filter over its range, the reactive constants of the dead-end

filter being so proportioned relative to the capacitance across the terminals of the operating frequency range that the mean value of the impedance across the terminals over the range is approximately the maximum that can be maintained over the range. 5

Other modifications and applications of the dead-end filter of the invention are described and claimed in applicant's applications Serial No. 203,595, Serial No. 203,596, and Serial No. 203,598, filed concurrently with the present application while a general circuit arrangement, for maintaining a high impedance over a wide frequency range across a pair of terminals having associated therewith inherent inductance tending to 10 limit the response of the system, is described and broadly claimed in applicant's copending application Serial No. 161,017, filed August 26, 1937, all assigned to the same assignee as the present application. 15

The novel features believed to be characteristic of the invention are set forth with particularity in the appended claims. The invention itself, however, both as to its organization and method of operation, together with further objects and advantages thereof, will best be understood by reference to the specification taken in connection with the accompanying drawings, in which Fig. 1 is a simplified, or equivalent, circuit diagram utilized to explain the general theory 20 of the invention; Fig. 2 is a graph illustrating certain of the operating characteristics of the circuit of Fig. 1; and each of Figs. 3-10, inclusive, illustrates a different embodiment of a coupling circuit utilizing the invention. 25

The principles of the theoretical relations underlying the invention are described most simply by reference to a nondissipative wave filter of the constant- k type. This filter may be assumed to have an infinite number of sections or 40 to be terminated with its image impedance to give the same effect. The input impedance of such a filter is uniform over the pass bands if the input termination is full-series or full-shunt as distinguished from the usual mid-series or 45 mid-shunt termination. The input impedance is the iterative impedance measured in series with a full-series arm or in parallel with a full-shunt arm, as distinguished from the conventional image impedance measured at mid-series 50 or mid-shunt. This input impedance may be regarded as a two-terminal coupling impedance, the remainder of the filter serving merely as a dead-end supplementary network utilized to secure the desired uniform impedance. 55

Any such filter of finite total band width can be arranged to include directly across its full-shunt arm, a capacitance of the value

$$C=2/R\Delta\omega \quad (1)$$

in which R is the mid-band image impedance and $\Delta\omega$ is 2π times the total width of the pass bands. The uniform full-shunt iterative impedance across the capacitance C has the magnitude

$$R=2/C\Delta\omega \quad (2)$$

This relationship expresses the theoretically maximum value of impedance that can be maintained across the capacitance C throughout frequency bands of total width $\Delta\omega$. In the case of a simple low-pass filter, the value of R is twice the reactance of the capacitance C at the cutoff frequency.

The problem reciprocal to building up impedance across a shunt capacitance is building up the admittance through an inductance. A filter can be arranged to include directly in series with all the other elements of its series arm, an inductance of the value

$$L=2R'/\Delta\omega \quad (3)$$

The uniform full-series iterative impedance through the inductance L has the magnitude

$$R'=L\Delta\omega/2 \quad (4)$$

This relationship expresses the theoretically minimum value of impedance that can be maintained through an inductance L over the frequency bands of total width $\Delta\omega$. In the case of a simple low-pass filter, this value is half the reactance of inductance L at the cutoff frequency. The specification will not be generalized to include derivations of expressions relating to maintaining a given value of impedance through an inductance, because all the relations herein-after given can be applied to this problem by the analogy which appears in the preceding formulae.

The image impedance of a filter of the type under discussion is purely resistive in the pass bands, though not uniform. On the other hand, the uniform iterative impedance has a substantial phase angle which is a lagging phase angle as referred to the impedance across a capacitance or the admittance through an inductance. The phase characteristic is that of a half-section of a constant- k filter.

A more general analysis is given hereinafter with reference to a simple low-pass filter, without any loss of generality in the foregoing concepts.

Referring now to the drawings, Fig. 1 shows the basic filter circuit in simplified form, the filter being represented schematically at 7 and having input terminals 8 and output terminals 9. The input termination C_m of filter 7 is a mid-shunt element and the input image impedance Z_i follows the constant- k characteristic. The output termination of filter 7 is either mid-series or mid-shunt and its image impedance Z_i' preferably follows an m -derived characteristic to match closely the output load resistance R_o . In developing the theoretical relations, this impedance matching is assumed to be exact in the pass bands, since any required degree of approximation is possible by means of multiple m -derivations.

For the sake of generality and clarity, the total capacitance C_o across the input terminals 8 may have any value and is divided in two parts, C_m comprising the mid-shunt capacitance termination of the filter, and C_n the external added capacitance, thus, only a part of the total capaci-

tance across terminals 8 is included in the filter as a mid-shunt element. The impedance Z is, therefore, across the total shunt capacitance, $C_o=C_m+C_n$. This impedance is to be built up with the aid of a dead-end filter acting merely as a passive auxiliary network.

The shunt capacitance C_m in the filter is the mid-shunt element of a terminal half-section. This half-section may be of m -derived type ($m < 1$) or of constant- k type ($m = 1$), since either type is available in a form whose mid-shunt termination presents the desired constant- k image impedance Z_i across shunt capacitance C_m . In such a half-section, the value of the mid-shunt capacitance is

$$C_m=m/R_{ow} \quad (5)$$

in which ω_c is $2\pi f_c$, where f_c is the cutoff frequency of the low-pass filter. The external shunt capacitance C_n can have any value as determined by the choice of the parameter n in the formula,

$$C_n=n/R_{ow} \quad (6)$$

Therefore, the total shunt capacitance is

$$C_o=C_m+C_n=(m+n)/R_{ow} \quad (7)$$

The factor $(m+n)$ may have any positive value. One of the parts may be negative, since the parts do not have to exist separately. Negative C_n merely means that the total capacitance C_o is less than the mid-shunt capacitance C_m of the filter. Equation (7) may also be written as

$$\omega_c=(m+n)/C_o R_o \quad (8)$$

$$R_o=(m+n)/C_o \omega_c \quad (9)$$

$$R_o C_o \omega_c = m+n \quad (10)$$

The image impedance Z_i depends only on R_o and ω_c , not on C_m and m , because it always has the constant- k characteristic

$$Z_i=\frac{R_o}{\sqrt{1-(\omega/\omega_c)^2}} \quad (11)$$

The image impedance is resistive in the pass band, capacitive in the attenuation band, and infinite at the cutoff frequency. It is convenient to use the parameter $x=\omega/\omega_c$ to denote the relative frequency in subsequent expressions. The relative impedance of C_n and Z_i in parallel is

$$\frac{Z}{R_o}=\frac{1}{R_o/Z_i+j\omega C_n R_o}=\frac{1}{\sqrt{1-x^2}+jxn} \quad (12)$$

This formula has a discontinuity at the cutoff frequency ($x=1$), where the Z_i term of the denominator changes from real to imaginary. It is seen that the form of the impedance characteristic depends only on

$$n=R_o C_{ow} \quad (13)$$

from Equation (6), and does not depend on

$$m=R_o C_{ow} \quad (14)$$

from Equation (5).

In the pass band ($x < 1$), Z/R_o is complex and its magnitude is

$$\left| \frac{Z}{R_o} \right|=\frac{1}{\sqrt{1+x^2(n^2-1)}} \quad (15)$$

If $n=1$, this is constant (unity). For greater values of n , it has the form of a simple resistor and capacitor in parallel, though the phase angle is not the same. The impedance has a lagging phase angle.

$$\delta=\tan^{-1}\frac{nx}{\sqrt{1-x^2}} \quad (16)$$

This is the same as the formula for a half-section

m-type filter except that the *m* of the filter is replaced by the parameter *n* which determines the relative value of C_m . If $n=1$, it simplifies to

$$b = \sin^{-1} x \quad (17)$$

5 In the attenuation band ($x > 1$), Z/R_o is imaginary and its magnitude is

$$\left| \frac{Z}{R_o} \right| = \frac{1}{\sqrt{x^2 - 1 + xn}} \quad (18)$$

10 It has a lagging phase angle, $b = \pi/2$. These characteristics cannot be realized exactly because the output image impedance Z'_i cannot match R_o outside the pass band. As the attenuation increases, this failure has less effect on the input impedance. Therefore, any degree of approximation to the theoretical characteristics outside the pass band can be realized with a sufficient number of sections designed to secure adequate attenuation.

15 Fig. 2 shows the theoretical impedance characteristics for various values of the parameter *n* between -1 and +4. It is noted that the values ± 1 yield uniform impedance in the pass band.

20 If the filter has a constant-*k* whole section on the input side, so that $m=1$, the values +1 and -1 for *n* correspond, respectively, to full-shunt and full-series termination. In the former case, the addition of C_n doubles the mid-shunt element, while in the latter case it cancels the mid-shunt element. The sign of the parameter *n* does not affect the magnitude of the impedance in the pass band, but it does determine the sign of the phase angle.

25 Since only positive self-reactance elements can be realized in a passive network, the value of *m* in the end half-section of a filter must be between 0 and +1. Since $m+n$ must be positive, the value of *n* must be between -1 and + ∞ .

30 Negative values of *n* make the impedance infinite at the frequency

$$x = \frac{1}{\sqrt{1 - n^2}} \quad (19)$$

35 At higher frequencies, the phase angle is reversed in sign, $b = -\pi/2$.

40 Any of the impedance characteristics of Fig. 2 are theoretically obtainable across a maximum value of total shunt capacitance if $m=1$, *n* having the value identified with the characteristic curve. If *m* is less than one, the total capacitance directly across the input terminals is less by the amount added indirectly across the input terminals through the other arms of the filter. Therefore, a uniform impedance equal to R_o in the pass band is obtainable across a maximum total capacitance, directly and indirectly in shunt, whose value is computed by letting $m=n=1$:

$$C_o = 2/R_{ow} \quad (20)$$

45 which corresponds to Equation 1. Any change of the total capacitance, by changing the value of *n*, causes an inverse change of the average impedance in the pass band, although its value R_o at zero frequency remains the same.

50 In the pass band, the impedance near the cut-off frequency is determined mainly by the value of *n*, that is, by the external shunt capacitance C_n . The image impedance Z'_i having less effect, the tolerance of mismatching between Z'_i and R_o at the far end of the filter becomes greater. Also, this tolerance increases with *n*. The number of sections in the filter affects the number of peaks and valleys in the actual impedance curve of Z , while the phase characteristics affect their spacing along the frequency axis.

5 Figs. 3-10, inclusive, show several arrangements of low-pass filters chosen to illustrate the various degrees of complication and refinement of performance. Fig. 3 shows an arrangement utilizing the invention wherein the dead-end filter is coupled to the external condenser C_n . The filter comprises an *m*-derived half-section, of which the condenser C_m is a mid-shunt element and is provided with a terminating resistor R_o of such value as to match the *m*-derived image impedance at the dead end of the filter over the low-frequency band. The parallel tuned circuit, which is a series arm of the *m*-derived section, is resonant slightly above the cutoff frequency of the system, preferably between the limits of 10

$$\sqrt{4/3} \text{ and } \sqrt{2}$$

15 times the cutoff frequency.

20 The filter of Fig. 4 comprises a typical practical application of the filter shown in Fig. 3 in 20 which it is utilized as a coupling impedance between vacuum tubes 10 and 11 which may be amplifying tubes in a low-pass amplifier designed to amplify a wide band of frequencies. The total inherent capacitance of the output circuit of vacuum tube 10 and the input circuit of vacuum tube 11 is represented by the condenser 12 shown in dotted lines. All the elements of the filter of Fig. 3 are present in the filter of Fig. 4, the condenser 12 having a capacitance equal to the total 25 capacitance of condensers C_n and C_m of Fig. 3. In the circuit of Fig. 4, the position of terminating resistor R_o and the parallel-connected inductance and capacitance elements of the *m*-derived section of the filter of Fig. 3 have been 30 transposed, the parallel-connected inductance and capacitance being indicated at 13 in Fig. 4. The remaining elements of the circuit of Fig. 4 are conventional and its operation will be apparent from the description of the low-pass filter 35 of the invention given above.

40 Figs. 5-10, inclusive, show other applications of the dead-end filter of the invention to more complex filter networks including filter full-sections or half-sections of several types as may be desirable to meet the requirements of particular systems. In Fig. 5 there is shown a dead-end filter of the invention comprising, in the order named, external condenser C_n , a constant-*k* half-section of which the condenser C_m is a mid-shunt element, an *m*-derived half-section indicated at m' in the drawings, and terminating resistor R_o the impedance of which matches the image impedance of the *m*-derived section at the dead end of the filter over the pass band.

45 In Fig. 6 there is shown a filter of the invention comprising, in the order named, external condenser C_n , a constant-*k* whole section of which the condenser C_m is a mid-shunt element, an *m*-derived half-section indicated at m' in 50 the drawings, and a terminating resistor R_o the resistance of which matches the image impedance of the *m*-derived filter section over the pass band.

55 The filter of Fig. 7 is in all respects equivalent 65 to that shown in Fig. 6 and is utilized as a coupling impedance between vacuum tubes 20 and 21 which may comprise tubes of a low-pass amplifier for amplifying a wide band of frequencies. The elements C_n and C_m have been combined 70 in the filter of Fig. 7 as the capacitance represented by condenser 22 shown in dotted lines. Condenser 22 may be comprised in whole or in part of the total inherent capacitance of the output circuit of tube 20 and the input circuit of 75

tube 21. Adjacent elements of similar kind of the circuit of Fig. 6 have been combined into one element in the circuit of Fig. 7. The position of terminating resistor R_o and the parallel inductance-capacitance circuit of the m -derived section of Fig. 6 have been reversed, the parallel inductance-capacitance circuit being denoted 23 in Fig. 7. A grid leak 24 is provided for vacuum tube 21 which may have an appreciable effect 5 upon the operation of the filter circuit shown. It will be understood that the effect of this resistor upon the operation of the filter can be taken into consideration in the design of the filter elements in the manner described in detail in the above-mentioned copending application, Serial No. 203,595.

In Fig. 8 there is shown a dead-end filter comprising, in the order named, external condenser C_n , an m -derived half-section indicated at m 20 in the drawings of which condenser C_m is a mid-shunt element, a double m -derived half-section indicated at m' in the drawings, and a terminating resistor R_o the resistance of which matches the image resistance of the dead-end filter very 25 closely over the pass band, and exactly at three frequencies in the band.

The filter of Fig. 9 comprises, in the order named, external condenser C_n , a constant- k half-section of which C_m is the mid-shunt element, 30 an m -derived half-section indicated at m' in the drawings, a double m -derived half-section indicated at m', m'' in the drawings, and terminating resistor R_o the resistance of which matches the image impedance of the filter over 35 the pass band.

The filter of Fig. 10 comprises, in the order named, external condenser C_n , a constant- k section of which condenser C_m is a mid-shunt element, an m -derived half-section indicated at 40 m' in the drawings, a double m -derived half-section indicated at m', m'' in the drawings, and terminating resistor R_o the resistance of which matches the image impedance of the filter over 45 the pass band.

It will be seen that the filters of Figs. 5, 6, 7, 50 9, and 10 have their entire external capacitance in shunt across the input terminals, that is, $m=1$ in the mid-shunt arm comprising C_m . These filters can be practically realized only if the inductance elements of the filter can be made with negligible shunt capacitance. Otherwise, the filters of Figs. 3, 4, and 8 can be utilized, which tolerate about 20% less shunt capacitance ($m=0.6$), in addition to that across 55 the inductance elements. It will also be noted that, in the filters of Figs. 4 and 7, the capacitance to ground from every junction point of the filter is included in the filter design. The filters of some of the other figures also can be arranged 60 to secure this advantage.

In the design of the dead-end filters of the invention, the preferred value of m in the m -derived sections is of the order of 0.6. Values of m between the limits of 0.5 to 0.7 result in a 65 matching of the image impedance of the m -derived filter section with the terminating resistor R_o at two points in the low-pass band. Filters having an m -derived termination with a value of m more than 0.7 cannot match the 70 terminal resistor R_o at more than one point in the low-pass band. Each additional m -derivation included in the filter termination makes it possible to match the image impedance with the terminal resistor at one additional point 75 in the low-pass band.

While there have been described what are at present considered to be the preferred embodiments of this invention, it will be obvious to those skilled in the art that various changes and modifications may be made therein without departing 5 from the invention, and it is, therefore, aimed in the appended claims to cover all such changes and modifications as fall within the true spirit and scope of the invention.

What is claimed is:

1. A two-terminal low-pass signal-translating system for operation over a wide range of frequencies comprising a pair of terminals common to the input and output circuits of said system and across which there is effectively capacitance 10 tending to limit the response of said system over said range, a dead-end filter having a predetermined image impedance over said range coupled to said terminals, said filter comprising only a part of said capacitance as a terminal mid-shunt element, and an impedance termination coupled to the dead end of said filter proportioned substantially to match the image impedance of said filter over said range, the reactive constants of said dead-end filter being so proportioned relative to said capacitance and the operating frequency range that the mean value of the impedance across said terminals over said range is approximately the maximum that can be maintained over said range.

2. A low-pass two-terminal signal-translating system for operation over a wide range of frequencies comprising substantial capacitance across said terminals tending to limit the response of said system over said range, a dead-end filter having a predetermined image impedance over said range coupled to said terminals, said filter comprising only a part of said capacitance as a terminal mid-shunt element, an m -derived impedance termination coupled to the dead end of said filter, a terminating resistor coupled to said impedance termination, said impedance termination being proportioned substantially to match the image impedance of said filter to said resistor over said range and exactly to match the image impedance of said filter to said resistor at two points in said range, the reactive constants of said dead-end filter being so proportioned relative to said capacitance and the operating frequency range that the impedance across said terminals over said range is substantially uniform and the maximum that can be maintained thereacross over said range.

3. A high-frequency amplifying system for operation over a wide range of frequencies comprising two vacuum-tube amplifiers having input and output terminals, one of said tubes having appreciable output capacitance and the other of said tubes having appreciable input capacitance, 55 said capacitances being effectively in parallel and tending to limit the response of said system over said range, a dead-end filter having a predetermined image impedance over said range and comprising only a part of said capacitances as 60 a terminal mid-shunt element, an m -derived impedance termination coupled to the dead-end of said filter, a terminating resistor coupled to said impedance termination, said impedance termination being proportioned substantially to match the image impedance of said filter over said range and exactly to match the image impedance of said filter at two points in said range, the reactive constants of said dead-end filter being so proportioned relative to said capacitances and 75

the operating frequency range that the transfer impedance between said amplifiers over said range is substantially uniform and approximately the maximum that can be maintained over said range.

4. A low-pass two-terminal signal-translating system for operation over a wide range of frequencies comprising substantial capacitance across said terminals tending to limit the response of said system over said range, a dead-end filter having a predetermined image impedance over said range coupled to said terminals and comprising only a part of said capacitance as a terminal mid-shunt element, an m -derived impedance termination in said filter comprising a parallel-resonant circuit as a series arm, a terminal resistor coupled to said impedance termination, said impedance termination being proportioned substantially to match the image impedance of said filter with said resistor over said range, the reactive constants of said dead-end filter being so proportioned relative to said capacitance and the operating range that the impedance across said terminals over said range is substantially uniform and approximately the maximum that can be maintained across said terminals over said range.

5. A low-pass two-terminal signal-translating system for operation over a wide range of frequencies comprising substantial capacitance across said terminals tending to limit the response of said system over said range, a dead-end filter having a predetermined image impedance over said range coupled to said terminals and comprising only a part of said capacitance as a terminal mid-shunt element, an m -derived impedance termination in said filter comprising a parallel-resonant circuit as a series arm, said parallel-resonant circuit being tuned between the limits of

$$\sqrt{\frac{4}{3}} \text{ to } \sqrt{2}$$

times the cut-off frequency of said range, a terminal resistor coupled to said impedance termination, said impedance termination being proportioned to match the image impedance of said filter with said resistor over said range, the reactive constants of said dead-end filter being so proportioned relative to said capacitance and the operating range that the impedance across said terminals over said range is substantially uniform and approximately the maximum that can be maintained across said terminals over said range.

6. A low-pass two-terminal signal-translating system for operation over a range of frequencies comprising substantial capacitance across said terminals tending to limit the response of said system over said range, a dead-end filter having a predetermined image impedance over said range coupled to said terminals and comprising only a part of said capacitance as a terminal mid-shunt element, an m -derived impedance termination for said filter comprising a parallel-resonant circuit as a series arm, said parallel-resonant circuit being resonant slightly above the cut-off frequency, a terminal resistor coupled to said impedance termination, said impedance termination being proportioned substantially to match the image impedance of said filter with said resistor over said range, the reactive constants of said dead-end filter being so proportioned relative to said capacitance and the operating range that the impedance across said terminals over said range is substantially uniform and approximately

the maximum that can be maintained across said terminals over said range.

7. A low-pass two-terminal signal-translating system for operation over a wide range of frequencies comprising substantial capacitance across said terminals tending to limit the response of said system over said range, a dead-end filter having a predetermined image impedance over said range coupled to said terminals, said filter comprising only a part of said capacitance as a terminal mid-shunt element, an m -derived impedance termination including a series-resonant shunt arm in said dead-end filter, a terminal resistor coupled to said impedance termination, said impedance termination being proportioned substantially to match the image impedance of said filter with said resistor over said range, the reactive constants of said filter being so proportioned relative to said capacitance and the operating frequency range that the impedance across said pair of terminals over said range is substantially uniform and approximately the maximum that can be maintained over said range.

8. A high-frequency amplifying system for operation over a wide range of frequencies comprising two vacuum tubes having input and output terminals, one of said vacuum tubes having appreciable output capacitance and the other of said vacuum tubes having appreciable input capacitance, said capacitances being effectively in parallel and tending to limit the response of said amplifier over said range, a dead-end filter effectively comprising a constant- k whole section having a predetermined image impedance over said range and including only a part of said capacitances as a terminal mid-shunt element, an m -derived impedance termination effectively comprising a parallel-resonant circuit as a series arm and coupled to the dead end of said filter, a terminal resistor for said impedance termination, said impedance termination being proportioned substantially to match the impedance of said filter with said resistor over said range, the reactive constants of said dead-end filter being so proportioned relative to said capacitances and the operating frequency range that the transfer impedance between said tubes over said range is substantially uniform and approximately the maximum that can be maintained over said range.

9. A two-terminal low-pass signal-translating system for operation over a wide range of frequencies comprising substantial capacitance across said terminals tending to limit the response of said system over said range, a dead-end filter having a predetermined image impedance over said range coupled to said terminals and comprising only a part of said capacitance as a terminal mid-shunt element, an m -derived impedance termination having a value of m of the order of 0.6 coupled to the dead end of said filter, a terminal resistor for said impedance termination, said impedance termination being proportioned substantially to match the image impedance of said filter with said resistor over said range, the reactive constants of said filter being so proportioned relative to said capacitance and the operating frequency range that the impedance across said terminals over said range is substantially uniform and approximately the maximum that can be maintained thereacross over said range.

10. A two-terminal low-pass signal-translating system for operation over a wide range of fre-

- 8   frequencies comprising substantial capacitance across said terminals tending to limit the response of said system over said range, a dead-end filter having a predetermined image impedance over said range coupled to said terminals, said filter comprising only a part of said capacitance as a terminal mid-element, an m -derived impedance termination having a value of m between 0.5 and 0.7 coupled to the dead end 5
10 of said filter, a terminal resistor for said impedance termination, said impedance termination

being proportioned substantially to match the image impedance of said filter with said resistor over said range, the reactive constants of said dead-end filter being so proportioned relative to said capacitance and the operating frequency range that the impedance across said terminals over said range is substantially uniform and approximately the maximum that can be maintained thereacross over said range. 10

HAROLD A. WHEELER.
